UNITED STATES PATENT OFFICE.

HARRY NORTHWOOD, OF WHEELING, WEST VIRGINIA.

SOCKET-COVER.

1,217,489.

Specification of Letters Patent. Patented Feb. 27, 1917.

Application filed September 19, 1916. Serial No. 120,945.

To all whom it may concern:

Be it known that I, HARRY NORTHWOOD, a citizen of the United States of America, and resident of Wheeling, county of Ohio, 5 and State of West Virginia, have invented certain new and useful Improvements in Socket-Covers, of which the following is a specification.

This invention relates to socket covers, 10 and it has for its primary object to provide a simple and inexpensive shade or globe-supporting cover for electric light sockets, which may be readily attached without removal of the socket from its suspension cord or other support.

A further object is to provide a combined 15 socket cover and shade support or holder involving parts which are telescopically nested or assembled, eliminating the necessity for providing screw threads therein.

With these and other objects in view, the invention resides in the features of construction, arrangement of parts and combination of elements which will hereinafter be exemplified, reference being had to the accompanying drawings, in which—

Figure 1 is a vertical section of a preferred form of the invention employed as a shade support;

Fig. 2 is a similar section of a slightly modified form;

Fig. 3 is an enlarged section on the line 3—3, Fig. 2; and—

Fig. 4 is a vertical section of a support 35 for a heavy globe, also embodying my invention.

Referring to said drawings, in which like designating characters distinguish like parts throughout the several views—

40 A indicates a tubular outer shell composed of sheet-metal and comprising a cylindrical body portion 1 having its lower end flared outward to form a supporting flange 2 adapted for receiving thereon in seated position

45 the upper portion of a shade or reflector 3 through the neck of which said shell has been introduced. Located at a suitable distance above said flange 2 is a series of annularly disposed ventilation openings 4, as shown.

50 The upper end of said shell terminates in an inturned flange 5 which is adapted to overlie in seated relation an annular external shoulder 6 formed in an in-

ner shell B of approximately conoidal form. Said shell B comprises a substantially cylindrical body portion 7, an integral dome portion 8 and the intermediate shoulder portion 6 above mentioned, said body portion being adapted for introduction in close-fitting, or telescoped, relation to the body 1 of 60 the outer shell with the dome portion 8 projecting upward above the flange 5.

The inner shell B is composed of two complementary members or sections which are preferably of identical form, as shown, said sections having their meeting edges connected at one side, as by a hinge, to permit of said sections being opened and closed with respect to each other without destroying their assembled relation. While any appropriate form of hinge connection may be employed, I prefer to use a wire loop 9 received in apertures 10 provided therefor in the adjacent vertical edges of the shell sections, as shown, said apertures being preferably slightly elongated horizontally to permit of increased freedom of opening movement of said sections with respect to each other. A central or axial opening 11 is provided in the dome portion 8 in which the 70 socket suspension member or wire is received while said dome portion rests directly upon the light socket (not shown).

To accommodate the outer part of the hinge and thus prevent the latter from interfering with the introduction of the shell B within the shell A, the body 7 of said shell B may be provided with an inwardly pressed circumferential rib 12 whereby is formed an external annular channel 13, in 80 which the hinge is located, as shown in Fig. 1; or, if preferred, slight horizontal indentations 13^a may be substituted for said channel, as shown in Figs. 2 and 3, said indentations being of proper length and depth. In 90 addition to serving the purpose mentioned, the rib 12, or the indentations 13^a, as the case may be, act to prevent the unhinged edges of the sections composing the shell B from passing each other, or assuming overlapped relation while being introduced within the outer shell A.

For concealing the collar or neck of the shade or reflector 3, a short flared apron-like ring or shield 14 may be disposed in loosely embracing relation to the body of the

shell A, the same being adapted to have its lower end or edge rest upon said shade or reflector. Said shield is provided with a series of suitably located ventilation openings 5 15, as shown.

In the modification shown in Fig. 4, which illustrates a combination socket cover and support for heavy globes and the like, the outer shell A' has its lower end flared outward 10 to form a bell-mouth skirt 16 designed to encircle the neck or collar of the globe, as 17, to be supported, said skirt having clamping screws 18 directed therethrough for assuming impinging relation to said neck or collar. In this form of device not only is the lower outwardly flared supporting flange 2 15 omitted, but the ring or shield 14 is also dispensed with.

In applying the invention, the shell A is 20 first introduced upward through the neck of the shade which is to be supported, and the shield 14 is then slipped downward over said shell. Said parts are then together elevated to a position on the suspension 25 cord a suitable distance above the socket. The sections of shell B are then spread apart at the side opposite the hinge for the introduction of said cord to a central or axial position, whereupon said sections are 30 again closed upon each other to embrace said cord at a point between the socket and the parts previously applied, as aforesaid. Said shell B is then slipped upward along said cord and is telescoped to seating position 35 within shell A; and, finally, the parts so assembled are permitted to drop to a position wherein the dome portion of shell B seats upon the socket.

What is claimed is—

- 40 1. A combined socket cover and shade support comprising an outer shell having its lower end adapted for assuming supporting relation to a shade and having an inturned flange at its upper end, and a second shell adapted for introduction in telescoped relation to said outer shell, said second shell comprising a body portion and an apertured dome portion with an intermediate shoulder, said shoulder being designed to assume underlying relation to said flange, said second shell being composed of two similar complementary connected sections adapted for axial opening and closing movement with respect to each other.
- 45 55 2. A combined socket cover and shade support comprising a tubular supporting shell, and a second shell telescoped within said supporting shell and having an apertured dome portion projected upward from the latter, said shells having interengaging means for limiting the extent of upward telescopic movement of said second shell, said second shell being composed of two connected complementary sections, and an apron-like shield loosely embracing the lower part of the tubular shell.
- 60 65 70 75 80 85 90 95 100 105 110 115 120 125

for axial opening and closing movement 65 with respect to each other.

3. A combined socket cover and shade support comprising a tubular supporting shell, and a second shell telescoped within said supporting shell and having an apertured dome portion projected upward from the latter, said shells having interengaging means for limiting the extent of upward telescopic movement of said second shell, said second shell being composed of two complementary sections having a hinged connection which permits axial opening and closing movement of said sections with respect to each other.

4. A combined socket cover and shade support comprising a tubular supporting shell, a second shell telescoped within said supporting shell and having an apertured dome portion projected upward from the latter, said shells having interengaging means for limiting the extent of upward telescopic movement of said second shell, said second shell being composed of two complementary sections, and means hingedly connecting said sections at one side only so as to permit axial opening and closing of said sections with respect to each other.

5. A combined socket cover and shade support comprising a tubular supporting shell, a second shell telescoped within said supporting shell and having an apertured dome portion projected upward from the latter, said shells having interengaging means for limiting the extent of upward telescopic movement of said second shell, said second shell being composed of two complementary sections, and means hingedly connecting said sections at one side, only so as to permit lateral separation of said sections at the opposite side for the introduction of a socket suspension member, said sections having means provided therein for receiving said connecting means in non-engaging relation with the tubular shell and for preventing the abutting free edges of said sections from assuming overlapped relation.

6. A combined socket cover and shade support comprising a tubular supporting shell, a second shell telescoped within said supporting shell and having an apertured dome portion projected upward from the latter, said shells having interengaging means for limiting the extent of upward telescopic movement of said second shell, said second shell being composed of two connected complementary sections, and an apron-like shield loosely embracing the lower part of the tubular shell.

7. A combined socket cover and shade support comprising a tubular supporting shell, a second shell telescoped within said supporting shell and having an apertured

dome portion projected upward from the latter, said shells having interengaging means for limiting the extent of upward telescopic movement of said second shell, an 5 inwardly pressed circumferential rib formed in said second shell whereby is formed an external annular channel, said second shell being composed of two complemental sec-

tions, and a hinge connecting said sections at one side and located in said channel. 10

In testimony whereof, I affix my signature in presence of two subscribing witnesses.
